James Bellon

ATTORNEYS.

UNITED STATES PATENT OFFICE

HARRY BRUEWER, OF NORWOOD, OHIO, ASSIGNOR TO THE CORCORAN MANUFACTURING COMPANY, OF NORWOOD, OHIO, A CORPORATION OF OHIO.

AUTOMOBILE-FENDER PACKAGE.

Application filed December 12, 1921. Serial No. 521,602.

To all whom it may concern:

Be it known that I, HARRY BRUEWER, a citizen of the United States, and a resident of Norwood, in the county of Hamilton and 5 State of Ohio, have invented certain new and useful Improvements in an Automobile-Fender Package, of which the following is a full, clear, and exact description, reference being had to the accompanying drawings, 10 forming part of this specification.

My invention relates to devices or methods for shipping fenders for automobiles, particularly for Ford automobiles.

The problem in shipping a set of four 15 fenders is that the crates are of such size, as ordinarily made up, that a comparatively few of them take up a full freight car, wherefore the price of car shipment is in excess of what it should be, since the carload 20 of fenders is well below the weight covered by the minimum carload price.

Referring to figures on present day car-load shipments of packages of four fenders in a single crate, I find that packed in rectangular crates there may be between sixty-eight and seventy crates of fenders placed in one thirty-six foot car, although the total weight of the fenders and crates is under 30 half what would be possible to place in the car at the minimum carload rates.

It is the object of my invention to provide a different form of package for fenders, which package is capable of a partial nesting. By the exact form to be later described, 35 I find that I can get one hundred and thirty-six crates into a car instead of sixty-eight to seventy. These figures relate to Ford car fenders, and would have to be modified for other shapes and sizes.

40 I accomplish the said object by that certain construction and arrangement of parts to be hereinafter more specifically pointed out and claimed.

In the drawings, 45 Figure 1 is a perspective view of one of my new packages.

Figure 2 is a side elevation showing the method of nesting the packages when placing them in a car.

50 I have shown the invention as applied to the fenders for Ford cars, because more Ford fenders are shipped than any other kind, and because the price at point of delivery is more important than for fenders in other 55 kinds of cars.

I wish it distinctly understood, however, that my invention will apply to fender packages generally, since all fenders have the common characteristics of being longer for the front set than the rear set, which feature 60 is taken advantage of in my invention.

Referring directly to the drawings, I have shown as a desirable form of openwork crate, a structure having a long rectangular portion formed of lengthwise boards 1, together 65 with suitable cross boards. A set of boards 2 of less length than the boards 1 are combined together with the cross boards 3 to make up a section of the crate of less height than the long portion. 70

The length of the long portion is such as to receive both of the front fenders, these being shown at 4 and 4^a, respectively, and set into the long portion of the crate with what will be the forward ends of each fender 75 extending toward the bottom of the crate. The fenders are, of course, a left and a right, which is also the case with the rear fenders.

The rear fenders are set into the crates with the one fender 5 having what will be 80 its rearmost end down, and the other fender 5^a with its like end up.

Looking at the crate from the side, the long front fenders are set with their faces to the rear of the crate, while the rear fenders are set with their faces to the side of the crate. The arrangement of fenders is thus a saving of space since the curves of front and rear fenders are arranged to be parallel with each other, and curves of the rear pair 90 are at right angles to the curves of the front pair.

Since the long fenders may be placed together closely and the rear or shorter fenders the same, they may be readily set into 95 the crate, and the crate nailed up so as to produce a package, half of which is considerably longer than the other half.

As shown in Figure 2, the crates are set into a car with the upper crates inverted 100 and the long portions set into the space left by the short portions of the crate beneath.

The cost of shipping Ford fenders for any distance has made it possible for concerns having low production cost because of quantity production to compete with local concerns in distant markets. 105

As a result of the use of my invention as compared with the old rectangular crates, 110

I am enabled at present freight rates for car-load shipments of fenders to save about eighty-nine cents per set on shipments from Cincinnati to New York, one dollar and fifteen cents per set on shipments from Cincinnati to New Orleans, and three dollars and nineteen cents per set on shipments to San Francisco.

This saving is a very large item in the fender business, particularly for Ford cars, since the price of fenders is very low and requires the closest economy in production and transportation cost.

There has been no attempt by me to describe the possible modifications of the package above described without departing from the spirit of the invention therein, but I wish to include such modifications as being within the scope of said invention, particularly where the modifications are merely to adapt the package to different sizes of fenders.

Having thus described my invention, what I claim as new and desire to secure by Letters Patent, is:—

1. A fender package comprising front and rear fenders, and a crate or the like surrounding the same, said crate having a long portion for the front fenders and a short portion for the rear fenders, whereby the finished package presents a space alongside the long portion for nesting of packages in shipment.

2. A fender package comprising a pair of

front and a pair of rear fenders, said front and rear fenders arranged with the curves thereof lying parallel for each pair and a crate having a long portion in which is housed the pair of front fenders, and a short portion in which is housed the pair of rear fenders, whereby the finished package presents a space alongside the long portion for nesting of packages in shipment.

3. A fender package comprising a pair of front and a pair of rear fenders, said front and rear fenders arranged with the curves thereof lying parallel for each pair, and the rear pair turned at right angles to the front pair, and a crate having a long portion in which the front pair is housed, and a short portion in which the rear pair is housed, whereby the finished package presents a space alongside the long portion for nesting of packages in shipment.

4. A fender package comprising front and rear fenders, and a crate or the like surrounding the same, said crate having a long portion for the front fenders and a short portion for the rear fenders, whereby the finished package presents a space alongside the long portion for nesting of packages in shipment, said crate being so proportioned that the short and long portions are of equal cross sectional area, so that the long portion of one crate may be set into the space of another crate inverted with relation to it.

HARRY BRUEWER.
